UNITED STATES PATENT OFFICE.

HARRY J. BUELL, OF MANSFIELD, OHIO, ASSIGNOR OF ONE-EIGHTH TO JOSEPHINE L. SPROAT, OF PITTSBURGH, PENNSYLVANIA, AND ONE-HALF TO WILLIAM ARTHUR PLASTOW, OF HAMILTON, CANADA.

COMPOSITE RAILWAY-TIE.

1,006,430.

Specification of Letters Patent. Patented Oct. 17, 1911.

Application filed February 18, 1911. Serial No. 609,830.

To all whom it may concern:

Be it known that I, HARRY J. BUELL, a citizen of the United States, residing at Mansfield, county of Richland, and State of Ohio, have invented certain new and useful Improvements in Composite Railway-Ties; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 My invention relates to improvements in composite railway ties, my object being to provide a tie forming a cushion support for the rails equal to that of a wood tie, and at the same time dispense with the greater 20 portion of the wood ordinarily employed in constructing a tie, and to this end the body of my improved tie consists of two metal plates between the extremities of which wood blocks are interposed and secured by bolts, the blocks being vertically arranged to project both above and below the metal plates. The upper surfaces of these blocks form seats for the rails, while their lower surfaces rest upon the prepared 25 rock base or bed forming the support for the ties. The space between the plates intermediate the cushion blocks is open, whereby the central portions of the plates are permitted to embed themselves in the roadbed, 30 thus preventing the ties from slipping. The absence of a filling between the cushion blocks, is important from the fact that there is virtually no central fulcrum over which the tie may be broken by pressure upon its 35 extremities. Furthermore, this feature makes the tie exceedingly cheap to manufacture.

Another feature of the tie consists in the employment of rail-anchoring plates which 40 extend across the tie on opposite sides of the rail, the said plates having hooked extremities which engage short angle bars secured to the opposite sides of the tie plates. These rail-anchoring plates are employed on the outside rails on curves, to 45 prevent the rails from spreading in response to the centrifugal force exerted by the train.

Having briefly outlined my improved construction, I will proceed to describe the

same in detail, reference being made to the accompanying drawing in which is illustrated an embodiment thereof.

In this drawing: Figure 1 is a side elevation of one of my improved composite ties showing the rails in cross section and spiked in place, the spikes being driven into the wood cushions forming seats for the rails. Fig. 2 is a top plan view of a section of track showing two ties of my improved construction. Fig. 3 is a section taken on the line 3—3, Fig. 2, looking toward the right or in the direction of the arrow, the parts being shown on a larger scale. Fig. 4 is a view similar to Fig. 1, but showing the rail-anchoring plates in connection with one of the rails. Fig. 5 is a top plan view of the same. Fig. 6 is a section taken on the line 6—6, Fig. 5, looking toward the right. Fig. 7 is a view looking in the direction of arrow 7, Fig. 6. Fig. 8 is a detail view of one of the side plates of my improved tie, one extremity of the plate being equipped with an angle bar for use in connection with the rail-anchoring plates. Fig. 9 is a perspective view in detail of one of the rail-anchoring plates.

The same reference characters indicate the same parts in all the views.

Let the numeral 5 designate each of two side plates separated to receive cushion blocks 6 interposed between their extremities and held in place by means of bolts 7 passed through registering openings formed in the side plates and the cushion blocks, nuts 23 being applied to the threaded extremities of the bolts. These blocks are somewhat thicker vertically than the side plates and project both above and below the same as shown at 8 and 9. By virtue of projecting above the plates, the blocks form cushion seats for the rails 10, while by virtue of extending below the plates, the cushion blocks engage the roadbed and give a cushion support to the rails equal to that of an all wood tie. Furthermore, since the lower edges of the plates do not engage the roadbed, there is no strain upon the bolts 7 which retain the cushion blocks in place. On a straight track the rails are secured to the cushion blocks by means of spikes 12; however, on curves the block upon which the outside rail rests is equipped with rail-anchoring plates 13 which extend across

the cushion block on opposite sides of the rail, the parts 14 directly above the cushion block, overlapping the base of the rail. These parts are provided with covered recesses 15 adapted to receive the heads of the spikes, which are therefore prevented from coming out as long as the plates 13 are in place. The outer extremities of these plates 13 where they project beyond the sides of 10 the body of the tie, are equipped with lugs 16 having perforations 17 to receive bolts 18 which pass below the rail in a direction parallel with the length of the tie, and are secured in place by nuts, thus locking the 15 two rail-anchoring plates in position. Each lug is also provided on its under surface with a hook 19 adapted to engage the under surface of the horizontal flange 20 of an angle plate 21 secured to the upper portion 20 of each side plate 5 of the tie by means of bolts 22. The rail-anchoring plates are slid into position by a movement lengthwise of the tie, after which they are connected by means of the bolts 18 as heretofore explained. The top flanges 20 of the angle plates 21 are of sufficient length to permit the hooked extremities of the rail-anchoring plates to engage the said flanges without interfering with the heads of the bolts 22. 30 These bolts 22 are passed through both side plates 5, as well as the cushion blocks 6, nuts 24 being applied to their threaded extremities. It will be understood that there is a pair of angle plates at each extremity of 35 each tie, whereby it becomes practicable to secure the rail-anchoring plates in place.

From the foregoing description the use of my improved composite tie will be readily understood. Where the track is straight, the 40 construction illustrated in Figs. 1, 2 and 3 is employed; while on curves, the extremities of the ties where the outside rails are located, are equipped with the rail-anchoring plates 13 to prevent the spreading of the 45 outer rail or lateral movement incident to the outward thrust or centrifugal force developed by the train.

Having thus described my invention, what I claim is:

50. 1. A composite railway tie comprising two separated plates, and fiber cushion blocks interposed between the extremities of the plates and projecting both above and below the latter, the said blocks being suitably secured to the plates, substantially as described.

60. 2. A composite railway tie comprising two separated plates, and fiber cushion blocks interposed between the extremities of the plates and suitably secured in place, the said blocks projecting both above and below the plates, the portion of the tie between the

cushion blocks being devoid of filling between the plates.

3. A composite railway tie composed of 65 metal plates, and cushion blocks interposed between the extremities of the plates, the said blocks being secured in place and projecting both above and below the said plates, the portion of the tie between the cushion 70 blocks being devoid of filling, and rail-anchoring plates applied to one extremity of the tie to prevent the outside rail from spreading on curves.

4. A composite railway tie composed of 75 wood and metal, the metal portion consisting of two plates, cushion blocks interposed between the extremities of the plates, the central portion of the tie between the plates being devoid of filling, rail-anchoring plates 80 extending across the top of the tie on opposite sides of the rail and overlapping its base, the extremities of the said plates having hooks and the metal plates of the tie being equipped on opposite sides with angle 85 plates which the hooked extremities of the rail-anchoring plates engage, the extremities of the latter being connected, for the purpose set forth.

5. The combination with a railway tie 90 and a rail seated thereon, of rail-anchoring plates applied transversely to the top of the tie on opposite sides of the rail and overlapping the base of the latter, the said plates having covered recesses to receive the heads 95 of rail-securing spikes, the opposite extremities of the rail-anchoring plates being connected and the tie being provided on opposite sides with short angle bars which are engaged by the extremities of the rail-anchoring plates, substantially as described. 100

6. A railway tie comprising metal plates spaced by cushion blocks interposed between the plates at their opposite extremities, and forming cushion seats for the rails, the said 105 blocks extending both above and below the metal plates, rail-anchoring plates extending across the tie on opposite sides of a rail, the extremities of the said plates projecting laterally beyond the tie and having hooked extremities, short angle bars secured to the metal plates on opposite sides of the tie, the extremities of the rail-anchoring plates being perforated, and bolts passed through the perforations in the opposite extremities of 110 each pair of plates, the bolts being located beneath the rail, substantially as described. 115

In testimony whereof I affix my signature in presence of two witnesses.

HARRY J. BUELL.
